UNITED STATES PATENT OFFICE.

SAMUEL PEACOCK, OF WHEELING, WEST VIRGINIA, ASSIGNOR TO WHEELING STEEL & IRON COMPANY, OF WHEELING, WEST VIRGINIA, A CORPORATION OF WEST VIRGINIA.

PROCESS OF DEGREASING THE MEAL USED IN CLEANING TIN PLATE.

No Drawing.

Application filed February 11, 1922. Serial No. 535,961.

To all whom it may concern:

Be it known that I, SAMUEL PEACOCK, a citizen of the United States, residing at Wheeling, in the county of Ohio and State 5 of West Virginia, have invented certain new and useful Improvements in Processes of Degreasing the Meal Used in Cleaning Tin Plate; and I do hereby declare the following to be a full, clear, and exact description 10 of the invention, such as will enable others skilled in the art to which it appertains to make and use the same.

This invention relates to a process of recovering the flour middlings or meal now 15 commonly used in absorbing the palm oil employed on tin plate during their manufacture and has for its object to provide a procedure which will be less expensive and more efficient than those heretofore proposed.

With these and other objects in view, the invention consists in the novel steps and combinations of steps constituting the process, all as will be more fully hereinafter 25 disclosed and particularly pointed out in the claims.

In order that the precise invention may be the better understood, it is said:

In the manufacture of tin plate, the steel 30 sheets that come from the bath of molten tin pass first through a bath of molten palm oil for the purpose of forming a film of oil thereon to protect the surface of the tin from contact with the air, while it is hot, the 35 object being to prevent any surface oxidation of the tin.

After the tin is cooled below its oxidation temperature, it is a common practice to remove this oil by subjecting the coated 40 sheets to a rubbing action with a low grade flour product known as middlings or meal. This material readily absorbs the palm oil and leaves the tin surfaces clean. But the meal becomes in time so saturated with the 45 palm oil that it can no longer be used for cleaning plates, and then it is discarded or sold for stock food and other purposes.

On the other hand, if these middlings could be thoroughly degreased and the oil 50 recovered, they could be used over and over again, their original cost thus saved, and the oil returned to the process. It has been proposed to recover this said meal or middlings by treating them with a solvent such

as naptha. But it has been found that 55 solvents such as naptha, gasoline, etc., contain some residual oils of relatively high boiling points that can only be removed by treating the meal with steam, or by heating said meal to a temperature sufficiently high 60 to drive off such oils. But it is found that the use of steam causes a hydrolysis of the starchy matters in the meal, thus destroying its oil absorbing qualities; and it has also been found that the driving off of the residual 65 oils by heat likewise destroys the useful properties of this said meal.

It is further found in practice that this oil saturated meal when treated with any solvents tried, contains numerous small particles or knots that remain saturated with the oil no matter how long the said solvent and meal is stirred together, so that only the objectionable steam or heat above mentioned has prior to this invention been found 75 effective in entirely removing the last portions of the palm oil.

According to this invention, on the other hand, I overcome the above objections by proceeding as follows:

I treat these saturated middlings with a purified benzol. I have further found that when these saturated middlings are suspended in this solvent, and beaten for a considerable time, say two or three hours, 80 in a suitable beating engine such as is used in making paper pulp, for example, such a complete contact between the knots of saturated middlings and solvent is effected that when the mass thus treated is subjected to 85 filter pressing, or to other separating apparatus adapted to remove the solvent a complete extraction of the palm oil is effected.

The benzol and palm oil having now been separated from the meal, the last traces of 90 said benzol may be eliminated by subjecting the mass to a relatively low temperature of, say, 50° C. or 60° C. in a vacuum of, say, 20 to 25 inches of mercury, after which the meal will be found to be restored to its 100 original clean condition. The palm oil dissolved in the benzol, as well as the benzol itself are readily recovered by any suitable and well known methods.

It is important in carrying out this process 105 that the meal is kept free from contact with water to prevent hydrolysis of the same, and that the benzol is extracted out of

contact with air to prevent dangerous mixtures of the same with air.

It is obvious that those skilled in the art may vary the details of the procedure without departing from the spirit of the invention, and therefore, I do not wish to be limited to the above disclosure except as may be required by the claims.

What is claimed is:—

- 10 1. The process of degreasing meal used in removing palm oil from tin plate which consists in mixing benzol with said meal; subjecting said mixture to the action of a beating engine until all the palm oil has been dissolved from said meal; and freeing said meal from said benzol, substantially as described.
- 15 2. The process of degreasing meal used in removing palm oil from tin plate which consists in mixing benzol with said meal; subjecting said mixture to the action of a

beating engine until all the palm oil has been dissolved from said meal; and freeing said meal from said benzol, comprising the subjection of said meal to the action of a 25 filter press, and to a temperature below that at which the absorbent qualities of said meal are injured, substantially as described.

3. The process of degreasing meal used in removing palm oil from tin plate which 30 consists in mixing benzol with said meal; subjecting said mixture to the action of a beating engine until all the palm oil has been dissolved from said meal; and freeing said meal from said benzol by first separating a substantial portion of said benzol from said meal, then heating the mass and subjecting it to suction, substantially as described.

In testimony whereof I affix my signature.

SAMUEL PEACOCK.
